UNITED STATES PATENT OFFICE

LURELLE GUILD, OF NEW YORK, N. Y., ASSIGNOR TO THE ALUMINUM COOKING UTENSIL COMPANY, OF NEW KENSINGTON, PENNSYLVANIA, A CORPORATION OF PENNSYLVANIA

DESIGN FOR A COFFEE POT OR SIMILAR ARTICLE

Application filed February 1, 1932. Serial No. 42,695. Term of patent 7 years.

To all whom it may concern:

Be it known that I, LURELLE GUILD, a citizen of the United States, residing at New York, in the county of New York and State of New York, have invented a new, original, and ornamental Design for a Coffee Pot or Similar Article, of which the following is a specification, reference being had to the accompanying drawings, forming a part thereof.

Fig. 1 is a side elevational, Fig. 2 an end elevational, and Fig. 3 a plan view of a coffee pot or similar article, showing my new design.

I claim:

The ornamental design for a coffee pot or similar article, as shown.

LURELLE GUILD.
